UNITED STATES PATENT OFFICE.

HARRY W. SMITH, OF WORCESTER, MASSACHUSETTS.

DESIGN FOR WOVEN FABRIC.

SPECIFICATION forming part of Design No. 26,780, dated March 16, 1897.

Application filed January 15, 1897. Serial No. 619,371. Term of patent 14 years.

To all whom it may concern:

Be it known that I, HARRY W. SMITH, a citizen of the United States, residing at Worcester, in the county of Worcester and Commonwealth of Massachusetts, have invented and produced a new and original Design for Woven Fabrics, of which the following is a specification.

In the drawings, Figure 1 is a face view of a section of fabric embodying my design. Fig. 2 is an enlarged view of a smaller section of the fabric, showing the unit of design.

The design consists of a series of heavy members 1, running across the face of the fabric and composed of a plurality of woof-threads not intertwined, and between them a series of lighter members 2, also composed of a plurality of woof-threads not intertwined.

There is also a series of heavy vertical members 3, composed of a plurality of warp-threads, and between them a smaller number of warp-threads 4, twisted together and embracing the woof members.

The effect of the fabric is of a series of squares with heavy vertical and horizontal members, which are divided into four substantially equal small squares by a lighter vertical and a lighter horizontal member.

What I claim is—

The design for woven fabrics substantially as herein shown and described.

HARRY W. SMITH.
